UNITED STATES PATENT OFFICE.

PETER LONERGAN, OF SILVERTON, COLORADO.

DRILL-CHUCK.

No. 895,381.

Specification of Letters Patent.

Patented Aug. 4, 1908.

Application filed August 27, 1907. Serial No. 390,369.

To all whom it may concern:

Be it known that I, PETER LONERGAN, a citizen of the United States, residing at Silverton, in the county of San Juan and State of Colorado, have invented new and useful Improvements in Drill-Chucks, of which the following is a specification.

The invention relates generally to an improvement in drill chucks, comprehending more specifically a drill chuck made up of separable sections adapted to be secured in co-operating relation to secure the drill in place.

The main object of the present invention is the provision of a drill chuck including a removable section adapted when in position to engage and lock the drill shank, the construction including a clamping ring or sleeve operative to secure the removable section in applied or drill-holding position.

Another object of the invention is the provision of a yieldable seat for the drill, whereby the latter may be properly centered in the chuck and the strain on the drill evenly distributed throughout that portion of the chuck.

The invention will be described in the following specification, reference being had particularly to the accompanying drawing, in which:—

Figure 1 is a longitudinal section of my improved drill chuck, the drill being shown in elevation, Fig. 2 is an end elevation of the same, with the drill in section, Fig. 3 is a section on the line 3—3 of Fig. 1, Fig. 4 is a plan of the chuck with the locking section removed, Fig. 5 is a perspective of the locking section, Fig. 6 is an end elevation of the chuck, illustrating the use of the spanner to properly seat the locking section for the application of the clamping sleeve.

Referring particularly to the drawings, wherein is shown the preferred details of construction of the present invention, my improved drill chuck comprises a body 1 of circular contour in transverse section, and slightly tapered from the free or drill-receiving end.

The body is formed with a longitudinally disposed recess 2, of approximately V-shape in transverse section, the apex or base of the depression being arranged about centrally of the body and of semi-cylindrical shape in transverse section, as at 3, said rounded depression 3 corresponding approximately to the diameter of the drill shank and being

adapted to receive the latter when the parts are assembled. The recess 2 opens through the surface of the body and through the relatively forward end thereof, the rear end of the recess terminating, however, in advance of the rear end of the body to leave a solid head 4 at said rear end. The relatively rear portion of the recess 2 is of greater transverse dimension than the forward portion, the walls of said recess being cut away to secure the additional width, thereby providing shoulders 5 in said walls, as shown in Fig. 4. The recess 2 at its juncture with the depression 3 is of the same transverse dimension throughout the length of the recess, the increased width of the recess being gradual from the depression 3 to the outer end of the recess.

In alinement with the depression 3 the head 4 is formed with a cylindrical bore 6, said bore being of slightly greater diameter than the diameter of the depression 3 and being adapted to receive the head of the drill shank, as hereinafter described. The base of the depression 3 is cut out to provide a rectangular socket 7, in which is fitted a resilient base strip 8, as a block of rubber or the like, the upper surface of the strip projecting normally above the surface of the depression 3 and being concaved in accordance with the curvature of said depression. The relatively forward end of the strip or block 8 is disposed in rear of the forward face of the body, while the rear end of the block coincides with the rear end of the depression, so that said block extends throughout the length of the depression except at the forward end.

9 represents a clamping section, corresponding in length and sectional contour to the recess 2 in the body, being, therefore, approximately triangular in transverse section with the relatively rear end 10 of greater transverse dimension at the upper end than the relatively forward end 11. The apex of the clamping section is of semicylindrical contour, as at 12, being of a curvature to snugly fit the shank of the drill, and, therefore, together with the depression 3 in the body practically completing a cylindrical bore to receive and secure the drill. The forward end of the body is formed with a bead 13, and at a point beyond the recess 2 the bead is provided with a radially projecting stud 14. The forward end 11 of the clamping section is also formed with a bead 15 similar to the

bead 13 and providing a continuation of the latter when the parts are assembled.

A locking ring or sleeve 16 is provided for coöperation with the chuck body, said sleeve being somewhat less in length than the length of the body and of an interior diameter to correspond with the exterior diameter of the body. The sleeve is slightly conical in longitudinal section, corresponding in this respect to the sectional contour of the body previously noted.

In conjunction with the drill chuck I contemplate the use of a particular style of drill, in that the shank 17 is terminally provided with an enlarged head 18 designed to fit snugly in the bore 6 of the head 4. In advance of the head 18 the drill shank is reduced to fit within the depression 3, being in advance of said reduced portion of octagonal or other angular shape in cross section.

With the parts constructed and arranged as described, and the sleeve 16 withdrawn onto the reduced portion of the chuck, and the clamping section removed, the operation of my improved chuck is as follows. The drill is inserted in the body, with the head 18 fitting in the bore 6. The drill shank in advance of the head rests upon the yieldable block 8, and as the upper surface of this block is normally disposed above the base of the depression 3, the drill shank is supported entirely by the block. The clamping section is then inserted in the recess 2, the portion 12 of said section resting upon the reduced length of the drill shank. A spanner, as 19, is then engaged with the pin 14 of the body, bearing beyond said pin on the outer surface of the clamping section, it being understood that owing to the normally increased height of the block 8, the outer surface of the clamping section is normally disposed beyond the surface of the body. Pressure is applied to the spanner with the result to force the clamping section down into the recess, until its outer surface is coincident with the outer surface of the body. The locking sleeve 16 is then moved longitudinally of the body, locking the clamping section in place and securing the drill chuck parts in operative position with the drill secured therein.

The initial blows of the drill tend to firmly seat the sleeve in locking position, the conical formation of the latter and the bead 13 serving to prevent disconnecting longitudinal movement of the sleeve.

In applied position it will be noted that the drill is practically supported on the yieldable block 8, thereby distributing the strain and jar incident to the use of the drill throughout the length of that portion held in the chuck.

This tends to prevent any undue strain at any particular portion of the drill and thereby avoids breakage of the drill incident to those chucks binding the drill shank at one or two points only. Furthermore, the bore 6 of the chuck is of somewhat greater diameter than that portion receiving the shank in advance of the head 18, so that when the drill is in place relatively longitudinal movement of the same is absolutely prevented.

The drill may be conveniently removed by simply forcing the sleeve 16 in the relatively rearward direction, freeing the clamping section 9 and permitting its convenient removal and consequent freeing of the drill.

Having thus described the invention what is claimed as new, is:—

1. A drill chuck comprising a body formed for a portion of its length with a recess, the lower portion of the recess being formed to receive a drill, a yieldable block mounted in the lower portion of the recess, means fitting in said recess to engage the drill, and means to lock the parts in applied position.

2. A drill chuck comprising a body formed for a portion of its length with a recess, the lower portion of the recess being formed to receive a drill, a yieldable block mounted in the lower portion of the recess, means fitting in said recess to engage the drill, and means to lock the parts in applied position, said latter means operating to compress the block.

3. A drill chuck having a drill receiving opening, a compressible block fixed in the opening to support the drill shank, and means for compressing said block in the securing of the shank in place.

4. A drill chuck formed with a drill receiving opening, and a block of rubber extending longitudinally of the opening to underlie the drill shank.

5. A drill chuck comprising a body formed for a portion of its length with a recess, the forward portion of the recess being of less width than the rear portion thereof, the lower portion of the recess being formed to receive a drill, a yieldable block mounted in the lower portion of the recess, a clamping section formed to fit in the recess and engage the drill, said section snugly fitting both the reduced and enlarged portions of the recess, and a locking sleeve slidably engaging the body and overlying the clamping section.

In testimony whereof, I affix my signature in presence of two witnesses.

PETER LONERGAN.
